UNITED STATES PATENT OFFICE.

BURDETTE D. LA FORCE, OF OTTUMWA, IOWA.

MOUTH GAG OR RETRCTOR.

Application filed December 1, 1922. Serial No. 604,197.

To all whom it may concern:

Be it known that I, BURDETTE D. LA FORCE, a citizen of the United States, residing at Ottumwa, in the county of Wapello 5 and State of Iowa, have invented a new and useful Improvement in Mouth Gags or Retractors, of which the following is a specification.

This invention has relation to surgical instruments, and more particularly to what is commonly known as a mouth retractor or gag, and comprises an appliance to be fitted to the head of a patient at the forehead and chin and adjusted to retain the mouth in an open position so that the mouth cannot be closed during examinations and operations made within the mouth upon the teeth, throat, trachea, bronchi, esophagus or stomach.

Numerous devices have been produced to perform the functions above stated, but with these appliances, so far as I am at present aware, it has been the practice to insert or position the instrument either wholly or partially inside the patient's mouth so as to engage both the upper and lower teeth, or the gums if teeth are not present. Such structures have numerous objections, the principal one of which is that with the use of retractors or gags which engage the teeth, or within the mouth of the patient accidents occur, sometimes unavoidably, involving the breaking of a tooth or teeth, the dislocation of the jaws or other injury to the mouth or lips, which accidents are never desirable and sometimes involve a very serious and wholly unnecessary source of danger. Another objection to the usual form of mouth retractor or gag is that the operator's view is frequently obstructed, and the parts of the appliance within the patient's mouth interfere materially with the ready employment of such operating instruments as the surgeon may be using. Also many of the present appliances are so constructed that the patient can move his or her head to positions that are undesirable to the dentist or surgeon performing the operations. It will at once be realized that such a movement on the part of the patient may be highly undesirable and is disturbing to the operator, and, while it is necessary to provide against

any such contingency, it should not be lost sight of, and it has been one of the objects of my invention to provide a structure 55 which is readily under the control of the surgeon, so that he may wholly release or re-adjust the position of the patient's head without loss of time.

It is to overcome the above-stated objections and to obtain the above mentioned adjustments and facilities that the present structure has been devised, and, therefore, the objects of this invention are, first, to provide a structure for retaining the mouth 60 in an opened position without having any part of the instrument coming in contact with the patient's upper teeth; second, to provide means for effectively maintaining the head of the patient in a rigid position while 65 holding the mouth open and at the same time affording facilities by means of which the surgeon may wholly disengage or readjust the patient's head without loss of time; third, to provide a mouth gag that will be 70 comfortable to the patient and at the same time has a minimum number of parts that will interfere with the work of the operator, and, fourth, to construct the apparatus so that after securing the patient in the desired 75 position the entire structure may be instantly released to relieve the patient in the event of choking or strangling. Other objects, of course, will be apparent to others skilled in this art after an understanding of the invention is had, and it may be stated that the appliance is easy to manipulate, simple in construction, being made of a minimum 80 number of parts, and is comparatively inexpensive to manufacture so that it may be 85 sold for a reasonable price. The foregoing and other objects are accomplished substantially in the manner hereinafter fully set forth, reference being now had to the accompanying drawings which form a portion of 90 95 this specification, in which—

Fig. 1 is a side elevation of my invention showing the same in use upon a patient with the mouth closed.

Fig. 2 is a similar view showing the relative position when the mouth has been opened by the gag.

Fig. 3 is a plan, partly in section, of the chin engaging bar and its mounting,

Fig. 4 is a view at right angle to Fig. 3, the right hand end portion being in section on line 4—4, Fig. 3.

Fig. 5 is a sectional view of my invention drawn partly in elevation, the section being on line 5—5, Fig. 1.

Fig. 6 is a fragmental view of the latching means for the forehead plate showing the same in a different position.

10 Fig. 7 is an edge view of the chin bar, and showing the manner of mounting the carrying arms upon the main support.

15 Fig. 8 is a fragmental view of my invention illustrating an accessory for use on patients having subnormal chin formation.

Fig. 9 is a fragmental view showing the manner of mounting the accessory upon the chin bar.

20 Figure 10 is a perspective of the accessory shown in Fig. 8 but detached.

In the accompanying drawings, similar reference characters have been employed to designate the same parts throughout the divers views, and by referring to Figs. 1 and 2 it will be seen the retractor or mouth gag is constructed in the following manner: To a head engaging harness or head plate (which may be either separate from or attached to a fixed support, such as an operating chair or table), is secured by means permitting the necessary pivotal and other adjustments, instrumentalities for operating between the upper and lower jaws and upper part of the head and neck for forcing the lower jaw downwardly and posteriorly and holding it in the desired position.

25 As will at once be seen practically none of the mechanism is within the patient's mouth causing a reduced danger of damage, such as the breaking or dislodging of the teeth or causing excoriation within the patient's mouth or throat, thus leaving the dentist or surgeon more room to manipulate instruments for examination and operation.

40 It will be understood, of course, that, while the same is not shown, means are provided whereby the retractor structure may be mounted adjustably upon the back or other convenient portion of a chair, table, or the like, or upon a portable stand, so that after the patient's mouth has been opened by the operator the head cannot be moved in any direction, but is held rigid to permit the dentist or surgeon to perform operations, but, nevertheless, the operator may quickly place the patient in any other desired position, or may instantly release him from the structure.

45 In order to support the structure upon a table, stand, or other device, a post 10 is provided, to the upper end of which is suitably secured a cross piece 11, and from the ends of this cross piece suitable laterally disposed vertical supporting plates 12, 12, extend. These plates 12 which are coun-

terparts may be of any desired shape, the ones shown being trefoil, and in the lower portion of the structure thus provided I prefer to mount a pillow, cushion, or other similar head-rest 13 upon which the head of a patient is positioned, substantially as shown in Figs. 1 and 2.

A flexible strap 14, preferably of thin flexible metal, is mounted by means of a pivot 15 upon the lobes of the left hand plate 12 (Figs. 1 and 2), and adjacent its pivot said strap is provided with an aperture through which a headed bolt 16 passes. The shank of said bolt passes through a segmental slot 17 in plate 12 that is concentric with pivot 15, and a wing-nut 18 is screwed upon the threaded portion of bolt 16 to lock the strap in adjusted positions. A slot 19 extending longitudinally of strap 14 receives a stud or pin 20 upon the adjacent side of a forehead or head clamp 21, and which is adjustably secured to the strap by means of a wing-nut 22 screwed upon the threaded end of stud 20 after the same is inserted in slot 19 in the strap. The forehead clamp comprises a plate of concavo-convex shape to conform to the shape of the patient's forehead, and is preferably made of very thin spring metal so that it will generally shape itself to the contour of this portion of the patient's head.

25 A strap 23 is slidably and pivotally mounted upon the opposite plate 12 by providing a longitudinal slot 24 in said strap that co-operates with a stud or pin 25 passing through a segmental slot 26 corresponding with and opposite the segmental slot 17 of the other plate, and which is formed concentric with the pivotal member 27 carried by the respective plate 12 and extending through slot 24 of the strap. This strap, as well as strap 14, is flexible, being preferably made of thin spring metal, and may be adjusted upon the plate longitudinally and pivotally, and is adapted to releasably secure the adjacent end or side portion of forehead clamp 21 in position. This is done by providing a hooked stud 28 upon said forehead clamp, the recess or depression therein being engaged by an eccentrically mounted cross-piece 29 carried by an operating handle 30 that is pivoted upon a fulcrum 31 adjacent the eccentric piece 29, and when in latched position the handle lies flat against the forehead clamp plate 21. In the event it is desired to release the patient, the forehead clamp may be unlatched by moving handle 30 away from clamp member 21, as shown in detail in Figs. 5 and 6.

30 Pivoted upon plates 12 by means of a fulcrum element 32 is a pair of reciprocating arms 33 that extend upwardly in substantially the direction shown in the drawings, and are provided with lateral

extensions 34 extending at substantially right angles to arms 33 and are threaded to receive the stop-collars 35 screwed thereon. Wing-nuts 36 are also screwed upon extensions 34 toward or spaced from stop-collars 35, and intermediate these two elements is mounted the bored but unthreaded sleeve 37 to which a cross piece 38 is secured and extends across the lower jaw of the patient, 5 when in position, toward the opposite extension 34. The bar 38 is shaped, as shown in the drawings, so that it will, when positioned upon the patient, rest in the depression on the lower jaw just above the chin, 10 which latter usually protrudes slightly, and said bar is releasably connected to extension 34 in the manner hereinafter described. The element for engaging the opposite extension 34 consists of a longitudinally split 15 sleeve comprising opposing parts 39^a and 39^b, the former carried upon the end of cross-bar 38 and the latter suitably mounted upon a handle element 40 pivoted upon a pin 41 carried on an extended portion of 20 bar 38 or upon the counterpart portion 39^a of the split sleeve, while a spring plate 42 maintains these parts in their relative adjusted positions, so that when the bar has 25 been placed across the patient's chin or lower jaw in the manner shown in Fig. 1, handle 40 which is in position to open the 30 sleeve, as shown in dotted lines in Fig. 4, is swung downwardly to cause the split sleeve to fold around and engage the adjacent 35 extension 34 between the adjustable stop-collar 35 and wing nut 36 carried by this extension.

The lower jaw engaging-bar 38 may be 40 adjusted longitudinally upon extensions 34 of arms 33, and when the desired position has been located the same may be locked in place. In order to open or retract the 45 mouth, the lower jaw is depressed by moving the arms downwardly upon their pivots 32 in the manner shown in Fig. 2 of the drawings. For facilitating this movement, I have provided handle members 43 extending laterally from arms 33 in the direction opposite but substantially parallel with extensions 34 and connect the outer ends of 50 said handles by a rod 44. These handles and rod form an operating frame and are positioned in such manner that they will clear the crown of the patient's head in any 55 of their adjusted positions, and after the patient's head has been firmly locked by the forehead clamp, this frame is moved upwardly, as in the direction of the arrow in Fig. 1, which causes a retraction of the 60 lower jaw and opens the mouth. Headed bolts 45 pass through segmental slots 46 in plates 12 concentric with the fulcrum pin 32 of arms 33 and through apertures in said arms so that after the jaw has been retracted 65 and the mouth opened the desired distance,

arms 33 may be locked in this position by tightening or screwing down wing nuts 47 carried upon the outer threaded ends of said bolts 45.

In some persons the chin recedes, instead 70 of protrudes, as in a normal subject. Cross-bar 38 would not be so effective upon a chin of this receding type, and to take care of such contingency, I have provided the accessory illustrated in Figs. 8, 9 and 10, which 75 consists of a transverse plate 48 that has an upper hooked end 49 to be positioned upon the teeth or gum of the lower jaw of the patient and which is provided with a pad 50 of rubber, or other similar soft material. The plate 48 is provided with a longitudinal slot 51 to permit of longitudinal adjustment 80 to fit the particular patient, and it is locked in its adjusted position by means of a cap screw 53 that passes through said slot 50 and is screwed into a threaded aperture or 85 recess 52 in chin bar 38, and in order to facilitate the adjustment of plate 48 the lower end thereof may be provided with an 90 oppositely bent lip 54 by which it may be manipulated to adjust it to the particular patient.

From the foregoing it will be obvious that 95 in patients having normal bone formation about the chin that the structure may be clamped in position to retain the head rigidly by means of head clamp 21 and its adjustable straps and the chin cross-bar 38 may be adjusted to fit the depression above 100 the chin in the lower jaw, after which handles 43 are raised to depress or retract the lower jaw and open the mouth in which position the structure is locked and no part of 105 the device will be inside the patient's mouth, which cannot be closed. The only instances in which the teeth or gum of the lower jaw are engaged by my retractor are in such deformities as the receding chin above alluded to and on unruly patients, in which event the hooked plate is employed, which does not in any way interfere with the operation 110 of the dentist, physician or surgeon. Should the patient indicate strangling or choking, the operator may at once release the retractor by unlocking split sleeve 39^a and 39^b and then unlatch the strap or band 23 from the head clamp so that the patient 115 may be free to move as under normal conditions.

What I claim is:—

1. A mouth-gag comprising a head rest having lateral side plates, a forehead clamp coacting with the side plates of said head rest, arms pivotally mounted intermediate their ends upon the side plates of the head rest, a cross-bar connecting said arms at one end and adapted to engage the patient's lower jaw, and a handle element rigidly connecting the opposite ends of said arms. 125

2. A mouth-gag comprising a head rest, a

forehead clamp coacting therewith, arms pivotally mounted adjacent the head rest, and a cross-bar hingedly mounted upon one of said arms and having a locking engagement with the other arm.

3. A mouth-gag comprising a head rest, a forehead clamp coacting therewith, arms pivotally mounted adjacent the head rest, a cross-bar hingedly mounted at one end upon one of said arms, means for adjusting said bar longitudinally upon said arm, and a locking device upon the opposite end of said bar for releasably securing said bar to the other arm.

15 4. A mouth-gag comprising a head rest, a forehead clamp coacting therewith and adjustable towards and away from said rest, arms pivotally mounted intermediate their ends adjacent said head rest, a cross-bar hingedly mounted at one end upon one of said arms, means for adjusting said bar longitudinally upon said arm, and a locking device upon the opposite end of said bar for releasably securing said bar to the other arm.

30 5. A mouth-gag comprising a head rest, a forehead clamp coacting therewith and adjustable toward and away from said rest, arms pivotally mounted intermediate their ends adjacent said head rest, a cross-bar hingedly mounted at one end upon one of said arms, a locking device upon the opposite end of said bar for releasably securing the same to the other arm, and means carried by said arms for adjusting said bar longitudinally thereof.

35 6. A mouth-gag comprising a pair of spaced side plates, a head rest connecting said plates, straps pivotally and adjustably carried by the respective plates, a forehead clamp connected to said straps, a pair of arms pivotally mounted upon said side plates, and a cross-bar connecting said arms

and adapted to engage the patient's lower jaw.

45 7. A mouth-gag comprising a pair of spaced side plates, a head rest connecting said plates, straps pivotally and adjustably carried by the respective plates, a forehead clamp of concavo-convex shape adjustably connected to said straps, a pair of arms pivotally mounted upon said side plates, and a cross-bar connecting said arms and adapted to engage the patient's lower jaw.

50 8. A mouth-gag comprising a pair of spaced side plates, a head rest connecting said plates, straps pivotally and adjustably carried by the respective plates, one of said straps having a longitudinally elongated slot, a forehead clamp having a threaded stud adjacent one end and projecting through said slot, a nut for maintaining said stud in adjusted positions in said slot, a pair of arms pivotally mounted upon said side plates, and a cross-bar connecting said arms and adapted to engage the patient's lower jaw.

55 9. A mouth-gag comprising a pair of spaced side plates, a head rest connecting said plates, straps pivotally and adjustably carried by the respective plates and one of said straps having a slot extending longitudinally thereof, a forehead clamp having a threaded stud projecting through said slot, a nut for maintaining said stud in adjusted positions in said slot, means for releasably connecting said clamp to the other strap, a pair of arms pivotally mounted upon said side plates, and a cross-bar connecting said arms and adapted to engage the patient's lower jaw.

60 Signed at Ottumwa, county of Wapello and State of Iowa, November, 1922.

BURDETTE D. LA FORCE.
